UNITED STATES PATENT OFFICE.

EMILE F. GENNERT AND M. WILFRED GLEASON, OF NEW YORK, N. Y.

DESIGN FOR GLASSWARE.

SPECIFICATION forming part of Design No. 12,349, dated July 5, 1881.

Application filed April 23, 1881. Term of patent 14 years.

To all whom it may concern:

Be it known that we, EMILE F. GENNERT and M. WILFRED GLEASON, both of the city, county, and State of New York, have originated and designed a Pattern for Glassware, which can be either etched or cut upon the same, of which the following is a full, clear, and exact description, reference being had to the accompanying drawing, making part of this specification.

The drawing represents a portion of the design as placed upon an illuminating glass globe, though the design can be adapted for nearly all glassware, such as goblets, pitchers, decanters, &c.

The design consists of the body and border, which may go continuously around the article in sections or panels, though the former mode is preferred. A represents a wicker or similar basket, and consists of a number of short parallel lines running diagonally from right to left. At their upper and lower ends similar parallel lines run diagonally from left to right, and at an angle with group of lines above and below, as shown. These lines may be lengthened or shortened, arranged either farther apart or closer together, or made wavy, instead of straight, without materially altering appearance of design.

E represents flowers and fruits, appearing to be contained in and hanging from basket A.

O represents a border, which may be used in connection with basket A and contents E, though, as this may not be adaptable in all cases, it is not essential.

Numerous floral and fruit designs are in use for the ornamentation of glassware; but these are generally arranged in bouquets and wreaths or garlands, and in some instances are represented in baskets, whose outline, however, is shown; but these baskets are comparatively small, and indicate either carved or metallic bodies. In this design, however, it is intended that the article to be ornamented shall itself constitute and appear to be a wicker basket containing fruits and flowers.

What we claim as our invention is—

A design for glassware, consisting of the representation of fruit and flowers with a wicker or similar basket, arranged and represented substantially as shown and described.

EMILE F. GENNERT.
M. WILFRED GLEASON.
